UNITED STATES PATENT OFFICE.

ROBERT JOHN MACDOWELL, OF MARSHALL, MICHIGAN.

DESIGN FOR A FORK.

SPECIFICATION forming part of Design No. 32,380, dated March 27, 1900.

Application filed January 11, 1900. Serial No. 1,151. Term of patent 14 years.

To all whom it may concern:

Be it known that I, ROBERT JOHN MACDOWELL, a citizen of the United States, residing at Marshall, in the county of Calhoun and State of Michigan, have invented and produced a certain new and original Design for a Fork; and I do declare the following to be a full, clear, and exact description of the invention, such as will enable others skilled in the art to which it appertains to make and use the same.

The invention relates to a new and original design for a fork; and it consists of a design of the shape and configuration shown in the accompanying drawings, in which—

Figure 1 is a plan view of a fork. Fig. 2 is a side elevation; and Fig. 3 is a cross-sectional view on line $x-x$, Fig. 1, looking in the direction of the handle.

20 The leading feature of the design comprises

the handle 1, which is arched on the arc of a circle from a to b , thence enlarged to form the head c , and bowed in a reverse direction from b to d . From a to e the handle is formed with a lateral concave swell f , and from e to g it extends downwardly and joins the head 2, which is approximately rectangular and is formed with beveled cutting edges 3 at its sides and with tapering tines 4 at its forward end.

30 What I claim is—

The design for a fork substantially as herein shown and described.

In testimony whereof I have hereunto set my hand in presence of two subscribing witnesses.

ROBERT JOHN MACDOWELL.

Witnesses:

DAVID CUNNINGHAM,
STEVE LANGRIDGE.
